UNITED STATES PATENT OFFICE.

CHARLES BOOZE, OF BUFFALO, NEW YORK, ASSIGNOR TO M. H. BIRGE & SONS, OF SAME PLACE.

DESIGN FOR WALL-PAPER.

SPECIFICATION forming part of Design No. 22,897, dated November 14, 1893.

Application filed October 7, 1893. Serial No. 487,518. Term of patent 3½ years.

To all whom it may concern:

Be it known that I, CHARLES BOOZE, a citizen of the United States, residing at Buffalo, in the county of Erie and State of New York, 5 have invented and produced a new and original Design for Wall-Paper, of which the following is a specification.

The design consists of a series of vertical stripes having ornamental edges and connected near their upper ends by scroll ornaments of vase-like form which are filled with flowers and leaves as represented in the accompanying drawing. A series of wreaths of flowers and leaves is arranged between the ornamental stripes and are connected by 15 sprays of a running vine hanging from said scroll ornaments as shown in the drawing.

What I claim is—

The design for wall paper herein shown and described. 20

Witness my hand this 2d day of October, 1893.

CHARLES BOOZE.
